UNITED STATES PATENT OFFICE.

CHARLES RICH, OF NASHVILLE, TENNESSEE.

TABULAR CALCULATOR FOR MEASUREMENT OF LOGS.

SPECIFICATION forming part of Letters Patent No. 331,332, dated December 1, 1885.

Application filed August 10, 1885. Serial No. 174,010. (No model.)

To all whom it may concern:

Be it known that I, CHARLES RICH, a citizen of the United States, residing at Nashville, in the county of Davidson and State of Tennessee, have invented a new and useful Improvement in Log-Measurers, of which the following is a specification, reference being had to the accompanying drawings.

My invention has relation to improvements in devices for measuring logs, timber, and the like; and the novelty consists in the construction, combination, and arrangement of the various parts for service substantially as hereinafter fully set forth, and particularly pointed out in the claims.

The object of my invention is to provide a device of the character stated which shall accurately measure the diameter of a log, a piece of timber, without the danger and annoyance of the operator mistaking the figures or measurement, so common in connection with the "log-stick" at present in use, and which shall be simple, strong, and durable in construction and efficient in operation.

25 In the drawings hereto annexed, Figure 1 is a perspective view of a log-measuring device embodying my invention. Fig. 2 is a central longitudinal section thereof, and Fig. 3 is a detached detail view of the slide. Figs. 4 and 30 5 are a front and end elevation, respectively, of a registering-dial particularly adapted for use in connection with my invention.

Like letters of reference indicate like or corresponding parts in the figures of the drawings.

35 Referring to the drawings, A designates a standard, preferably rectangular in form, as shown, having a scale containing the necessary divisions into feet or inches, if preferred, as at a, having a handle, a', at its upper end and a foot or projection, a'', at its lower end, said foot being suitably secured to the standard, and having a beveled or sharpened upper surface, as at a³, and a pointed outer end, as at a⁴.

40 B designates the slide, carrying at its lower end a registering-foot, b, of similar shape and construction, the lower face of said foot being beveled, as at b', and adapted to meet or register with the beveled upper face of the standard-foot a''. The slide B comprises two pieces, B' B'', arranged on the front and rear faces of

the standard, respectively, and connected together at their lower ends by side plates, B³, secured to their edges by nails, screws, or otherwise. The front plate, B', has an opening, b², through which the divisions or marks on the scale can be seen. The rear plate, B'', is longer than the front wall, and at its upper end it has a handle or turned portion, c.

55 Between the meeting surfaces of the standard and back plate, B'', is arranged a spring, C, adapted to hold the slide in any position on the standard, on which it is adapted to be moved up or down by hand in measuring the logs or timber. One end of the spring is pivoted or secured, as at c', to the back plate, B'', of the slide, leaving the opposite end free to bear against the rear face of the standard and hold the slide in position thereon.

60 The operation is as follows: The lower end or foot of the standard is fitted under one side of the log or piece of timber, and the slide is moved up or down until its foot or pointer rests on the opposite side of the log or timber to that on which the foot of the standard rests, 65 the diameter or length of the log being indicated on the scale a of the standard, and observed through the opening in the front plate, B', of the slide.

70 I will now proceed to describe the dial or scale shown in Figs. 4 and 5 of the drawings.

D designates a dial-plate, in the form of a segment, having a reduced lower end, which is pivoted at d to a handle, E, the dial-plate lying beneath the bar and fitting closely against the under face thereof. The handle E preferably comprises a flat rectangular bar having its lower end finished or turned to provide a hand-piece, as at e, and bifurcated or slotted at its opposite end, as at E', a cross-bar, e', 85 connecting the arms of the slotted portion near their outer ends, the slotted portion E' being formed in the middle of the bar, extending longitudinally thereof.

90 F designates a plate secured by means of screws or nails to one of the arms of the slotted or bifurcated portion, and having a series of forwardly-projecting perforated lugs, f, separated from each other by a series of spaces intermediately arranged between the lugs.

100 A designates a series of plates or flaps

adapted to lie parallel with each other and transversely across the longitudinally-slotted portion of the handle-bar E. Each of the plates may have round or pointed front ends, 5 as at g, and at their rear ends they are notched at each side, as at g', and provided with a rearwardly-projecting pivotal lug, g'', perforated transversely, and adapted to fit between two of the lugs of the plate F in the space 10 between the same.

H designates a pivot rod or bolt passed transversely through the lugs of the plates F G to pivotally connect the several parts together without danger of displacement.

15 It will be observed that each plate can be thrown back out of line with its fellow plates and independently thereof without disturbing the same. The notched portions of the flap enables the lug to fit snugly between the lugs 20 of the plate F, and to allow said flaps to lie closely together, and hide or cover entirely the slotted portion E' of the bar E.

The dial-plate is divided into a number of spaces, h, by a series of curved lines, i i, 25 drawn from side to side thereof, and concentric with the outer curved edge thereof and with each other, and a series of transverse slanting lines, j j, which cross and intersect the lines i i, as shown, and thus provide the 30 spaces, the slanting lines j converging toward the pivot of the dial-plate.

At the outer curved edge and the side edges of the dial-plate is indicated the diameter of the logs or timber, and the length thereof, respectively—that is to say, on the upper outer edge of the dial-plate is placed in each space a number indicating the diameter of the log, 35 as from 16 to 25, and on the side edges thereof is placed a number in each of the spaces indicating the length of the log, as from 10 to 18.

The scale herein shown is made and arranged according to the "Cumberland river measure;" but it is obvious that the rule known to the art as "Scribner's rule," or other scale 45 may be substituted therefor without departing from the principle of my invention.

The device described is used conjointly with the measuring device, and by employing the same the number of feet in a piece of 50 timber or log of a given dimension can be immediately ascertained without the necessity of computing the measurements. The space at the intersection of the lines contains a number which is the product of the length and 55 diameter of a log or piece of timber.

The operation of this part of my device is as follows: To ascertain the number of feet in a log of given dimensions, which have been ascertained by the device shown in Figs. 1, 2, 60 and 3, and the handle moved to lie parallel with the vertical lines indicating the diameter of the log, and the flap or plate lying over the line which contains the number indicating the length of the log, is turned back to expose the 65 figures indicating the number of feet in the log.

In the accompanying drawings I have illus-

trated the scale known to the art as the "Cumberland river scale," which contains approximately the number of feet in a log of given 70 dimension after the slabs or pieces on the sides or edges of the log have been cut off, thus allowing for the waste, &c.

To illustrate the use of the device, we will suppose the log is fourteen feet in length on 75 the side and nineteen inches in diameter. The dial-plate or the handle is turned on its pivot until the forward slotted end of the handle lies immediately over the figure 19, at the upper edge of the dial, as shown in the drawings. The flap G, lying over the figure at the intersection of the line containing the figures 14 and 19, is turned back on its pivot, thus exposing the figure 149, which indicates approximately the number of feet in the log or 85 piece of timber, according to the scale employed, after deducting the quantity lost by waste in sawing the logs.

If desired, each of the flaps may contain the figure which shows the length of the log, 90 as shown in Fig. 4, and the front end of the bar E may be cut away, as at E', to disclose through the same the figure indicating the diameter of the log.

Various changes in the form and proportion 95 of parts and details of construction may be made without departing from the principle or sacrificing the advantages of my invention, the essential features of which will be readily understood from the foregoing description, taken 100 in connection with the drawings.

I do not desire in this application to claim the devices shown in Figs. 1, 2, and 3 of the drawings, as I would have it understood that I reserve the right to embrace the same in a 105 subsequent application.

Having thus fully described my invention, what I claim as new, and desire to secure by Letters Patent of the United States, is—

1. In a log-calculating device, the combination of a dial-plate having at its edges series of ordinals corresponding to the dimensions of the log, a slotted handle to which the dial-plate is pivoted, a rod secured to the handle adjacent the slot therein, and a series of independently-pivoted flaps arranged to close the slot independently of each other to expose the figure on the dial beneath the flap, as set forth. 115

2. In a log-calculating device, the combination of the dial-plate having series of figures at its edges corresponding to the dimensions of the log and a scale to indicate the number of feet of lumber board measure 120 therein, slotted handle pivoted to said dial-plate and a series of independently-pivoted flaps having a figure to indicate one of the dimensions of the log and adapted to be thrown back to expose the figure lying beneath the said flap on the dial-plate, as set forth. 125

3. In a log-calculating device, the combination of a dial-plate having series of figures at its upper and side edges corresponding to the dimensions of the log and a scale to indicate the number of feet of lumber board measure 130

therein, a handle pivoted to said dial-plate and having a longitudinal slot and an outer cut-away end, E², and a series of independently-pivoted flaps having a figure to indicate one of the dimensions of the log and adapted to be thrown back to expose the figure on the scale lying beneath the said flap on the dial-plate, as set forth.

In testimony that I claim the foregoing as my own I have hereto affixed my signature in presence of two witnesses.

CHARLES RICH.
